UNITED STATES PATENT OFFICE.

JAMES A. MACKILILICAN AND FRANK L. LIPSEY, OF HIBBING, MINNESOTA.

EXCAVATING MACHINE.

Application filed March 16, 1921. Serial No. 452,875.

To all whom it may concern:

Be it known that we, JAMES A. MACKILILICAN, and FRANK L. LIPSEY, both residing at Hibbing, in the county of St. Louis and State of Minnesota, have invented new and useful Improvements in Excavating Machines, of which the following is a specification.

This invention relates to an excavating and loading machine of the so-called shovel or scoop type and built relatively low so that it may be used underground in tunnels and mines, subways, drifts, and the like.

One object of the invention is to so arrange the parts of the machine that the center of gravity is between the wheels of the truck on which the parts are mounted or to the rear of the fulcrum point of the shovel lifting arms and thus reduce the over-all length of the machine and the amount of counter-weight required to balance the machine as the shovel or scoop is raised into and out of loading position above the truck.

Another object of the invention is to provide mechanism for imparting a steady straightforward thrust to the scoop or shovel and to do this with the minimum amount of power by having an indirect connection between the motor and scoop through a gear train.

A further object of the invention is to arrange the parts so that the turn-table on which the shovel or scoop is mounted may be swung around to either side of the truck or car a sufficient distance to reach working places at the sides of the car and thus facilitate excavating in corners and along the sides of a drift, and furthermore to enable the machine to work around a curve.

The invention consists further in the matters hereinafter described and more particularly pointed out in the appended claims.

In the accompanying drawings—

Fig. 1 is a vertical longitudinal sectional view of an excavating and loading machine constructed in accordance with our invention;

Fig. 2 is a horizontal sectional view taken on line 2—2 of Fig. 1;

Fig. 3 is a top plan view of one of the gear shifting frames, to be hereinafter described;

Fig. 4 is a sectional view taken on line 4—4 of Fig. 3;

Fig. 5 is a rear view of the machine;

Fig. 6 is a vertical sectional view taken on line 6—6 of Fig. 1;

Fig. 7 is an elevational view of one of the shovel or scoop arms, viewing the same from the inside thereof;

Fig. 8 is a side view of the machine showing the scoop or shovel arms raised into dumping position;

Fig. 9 is a perspective view showing the manner in which the gear shifting mechanism is actuated;

Fig. 10 is a top plan view of the truck frame, showing the pivoted bolster in the position occupied when the shovel or scoop is directly in front of the machine and in its starting position;

Fig. 11 is a like view of the truck frame, showing the bolster swung into a position occupied when the shovel or scoop is at one side of the machine;

Fig. 12 is a plan view of that part of the truck frame provided with the grooved track for the rollers on the bolster;

Fig. 13 is a plan view of the rack associated with the truck frame;

Fig. 14 is a perspective view of the bolster; and

Fig. 15 is a vertical sectional view taken on line 15—15 of Fig. 10.

The machine shown in the drawings comprises a truck or carriage 1 having wheels 2 to run on rails 3. Above the truck 1 is a horizontal deck 4 having pivotal connection with the truck 1 in the manner to be hereinafter described. Secured to the deck 4 are two upright standards 5, 5 arranged on opposite sides of the deck. Extending between and journaled in said standards are two horizontally arranged shafts 6, 7, as shown in Fig. 1.

On each side of the deck 4 is a shovel or scoop arm 8 having its inner end curved upward, as shown in Fig. 7, and journaled on the shaft 6. When the arms 8 are lowered position they extend horizontally forward from the deck 4, as shown in Figs. 1 and 2. Between the arms is a shovel or scoop 9. This is supported by the arms by being secured to roller carriages 10, one on each side thereof and mounted to roll endwise in elongated slots or trackways 11 in the arms. To move the shovel or scoop 9 endwise of the arms, both forward and backward, we provide for each arm a cable 110

12, which is preferably located inside of the arm, as shown in the drawings. Each cable 12 is trained over a plurality of grooved sheaves 13 carried by the associated 5 arm and also about a grooved pulley or sheave 14 at the inner end of the arm and fixed on the shaft 6. Secured to each side of the shovel or scoop 9 below the roller carriage 10 is a bar 15, to the opposite ends 10 of which are connected the ends of the associated cable 12, so that when the shaft 6 is rotated in one direction, the shovel or scoop 9 will be moved toward the outer ends of the arms 8, and when rotated in the opposite 15 direction it will be moved toward the inner ends thereof.

For raising the shovel or scoop 9 into dumping position above the truck 1, as shown in Fig. 8, we provide two segmental 20 racks 16, 16, both on the shaft 7. The racks have acute slots 16^a for the shaft 6 to extend therethrough and not interfere with the turning of the racks. These racks are arranged adjacent the standards 5, inside 25 thereof, and there is one for each arm 8. Each rack has an outwardly projecting portion 17 connected with the associated arm 8 by a link 18, as shown in Figs. 1 and 8. The links are connected together above the 30 arms by a yoke 18^a. As clearly shown in Fig. 1, the point of connection between each arm 8 and its link 18 is between the ends of the arm or forward of the pivotal or fulcrum point 6, so that power is applied between the 35 ends of the arms when raising the same.

Fixed on the shaft 6 is a worm gear 19 in mesh with a worm 20 on an inclined shaft 21 journaled in a bracket 22 on a horizontal cross-bar 23 supported above the deck 4, as 40 shown in Fig. 1. The lower end of the inclined shaft 21 extends into an open frame 24 through an elongated slot 25, as shown in Figs. 3 and 4. This permits the frame 24 to be moved transverse of the shaft 21, 45 and for this purpose said frame is slidably mounted on a cross-bar 26 supported above the deck 4 below the rod 23, as shown in Fig. 1. Fixed on the inner end of the shaft 21, in the frame 24, is a gear wheel 27, and 50 on opposite sides thereof are gear pinions 28, 28^a. These are fixed on shafts journaled in the frame, and such shafts have friction discs 29, 29^a. These discs are on opposite sides of a main friction disc 30 fixed on the 55 main driven shaft of an electric motor 31 or other prime mover mounted on the deck 4. When the frame 24 is in the position shown in Fig. 3, the gear wheel 27 is out of mesh with both of the gear pinions 28, 28^a, and 60 consequently the friction discs 29, 29^a are out of engagement with the interposed main disc 30 and no power is transmitted to the shaft 21 by the motor 31. When the shovel or scoop 9 is in its starting position, as 65 shown in Fig. 1, and it is desired to give the

scoop a straightforward thrust into the material to be excavated, the frame 24 is shifted to move the gear pinion 28 into mesh with the gear wheel 27, and this of course moves the friction disc 29 into frictional engagement with the main disc 30. As a result, the worm gear 19 is rotated in the direction required to exert a pull on the cable 12 to move the shovel or scoop in a forward direction. To reverse the movement of the 75 scoop, that is, to return it to its position back toward the inner ends of the arms, the frame 24 is shifted in the other direction to bring the gear pinion 28^a into mesh with the gear wheel 27 and the friction disc 29^a 80 into engagement with the main disc 30.

In Fig. 9, we have shown one way in which this frame 24 may be shifted manually. At one side of the deck 4 is a hand lever 32 pivoted on a bracket 33 secured to the deck. A link 34 connects the lower end of the lever 32 with the frame 24, and by moving the lever back and forth it is obvious that the frame 24 will be shifted endwise. To hold the lever 32 in any one of three predetermined positions, there is a notched segment plate 35 secured to the bracket 33.

Extending across the deck 4 and journaled thereon is a shaft 36, as shown in Figs. 1, 2 95 and 5. This shaft is to the rear of the segmental racks 16, and fixed on the shaft are two gear wheels 37, 37, one in mesh with each of the segmental racks 16. Fixed on the shaft 36 is a worm gear 38 in mesh with a worm 39 on an inclined shaft 40 having its upper end extending into a shift frame 41. The upper end of the shaft 40 is provided with a gear wheel 42 arranged between gear pinions on shafts journaled in the frame 41 and having at their outer ends friction discs 43, 43^a on opposite sides of the main driving disc 30, as shown in Fig. 2. This frame 41 is shifted in the same manner as the one previously described by a hand lever 44 connected with the frame by a link 45. When the frame 41 has been shifted to bring the friction disc 43 into engagement with the main disc 30, power is then transmitted to the shaft 40 from the motor 31, and through the gear train described, the segmental racks 16 are turned in a direction to raise the arms 8 up above the machine into dumping position. When the frame 41 is shifted in the opposite direction so as to bring the disc 43^a 115 into engagement with the main disc 30, the operation is reversed and the arms 8 are brought down into position extending forward in front of the machine, as shown in Fig. 1.

The deck 4 is pivotally connected with the truck or carriage 1 in the following manner, so that the deck may be turned in a horizontal plane to either side of the truck 1 in order that the shovel or scoop 9 may reach 130

working places at the sides of the machine. The truck or carriage 1 has an open frame 46 made preferably of structural steel, channel shape, as shown in the drawings. Within 5 in this frame 46 is arranged a casting 47 having the general shape shown in Figs. 10, 11 and 12. This casting has a rear cross-member 48, which extends across the frame 46, and said member 48 has two forwardly 10 projecting ears or lugs 49, 49^a spaced apart and being adjacent the ends of the cross-member 48, as shown in said figures. Integral with and extending forward from the cross-member 48 is the curved part 50 of 15 the casting 47, and this part is provided with an inwardly opening groove 51 being continuous from one end of the member 50 to the other and following the general curvature thereof. Located in the opening within 20 the member 47 is a bolster 52 having at its ends outwardly extending pins 53, on which are journaled rollers 54, which travel in the curved trackway 51. At one end, the bolster 52 has an inwardly extending portion 55 25 spaced vertically below the body part of the bolster and connected by a pivot pin 56 with a link 57, which in turn is connected by a pivot pin 58 with the forwardly projecting lug 49 of the cross-member 48. 30 Above the link 57 is a link 59 connected by a pivot member 60 with the bolster 52 adjacent its end opposite the end with which the link 57 is connected. The other end of the link 59 is connected by a pivot member 35 61 with the other forwardly projecting lug 49^a of the cross-member 48. The deck 4 is made open and of structural steel elements including longitudinal I-beams 62 supported above the bolster 52 by brackets 63, as shown 40 in Fig. 15.

Arranged on the truck or car 1 to the rear of the bolster 52 is a rack 64 having the curvature shown in the drawings and more particularly in Figs. 10, 11 and 12. This 45 rack 64 has a rearwardly extending stiffening flange 65, which also serves as a guide rail for a grooved roller 66 journaled in a bracket 67 secured to the deck 4 at the rear thereof, as shown in Figs. 1, 5 and 8. Opposite the bracket 67 on the inside of the deck 50 and secured thereto is a bracket 68, in which is journaled a vertical shaft 69 having at its lower end a pinion 70 in mesh with the rack 64. The curved portions of the castings 47 55 and 64 are arcs with centers at the pivot pins in the ears 49, 49^a farthest removed therefrom. On the upper end of the shaft 69 is fixed a worm wheel 71 in mesh with a worm 72 in a rearwardly extending inclined 60 shaft 73 journaled in a bracket supported on a part of the deck frame, as clearly shown in Fig. 2. At the upper end of the shaft 73 is fixed a gear wheel 74 located between the gear pinions 75, 75^a, which are mounted 65 on shafts journaled in a shift frame 76 sim-

ilar to the shift frames 24 and 41 heretofore described. The shafts on which the gear pinions 75, 75^a are mounted are also provided with friction discs 77, 77^a arranged at opposite sides of a main driving disc 78 70 of the electric motor 31. The frame 76 is shifted to move the gear pinions 75, 75^a alternately into and out of mesh with the gear wheel 74 by means of a pivoted hand lever 79 connected with the shift frame by a link 75 80 in the same manner as shown in Fig. 9.

The machine shown and described operates as follows. When operating against a bank or pile of material to be excavated directly in front of the machine, the latter 80 is run up into a position in front of such material with the arms 8, 8 lowered so as to extend horizontally straight in front of the machine and the shovel or scoop 9 in its starting position back in front of the truck 85 1, as shown in Fig. 1. At this time all of the hand levers 32, 44, and 79 are in the middle notch in their respective segment plates 35, and the gear train is in neutral 90 position so that no power is transmitted to the operative parts of the machine by the motor.

To fill the shovel or scoop 9 with a load, the lever 32 is pulled outward from the machine to move the disc 29 into frictional engagement with the driving disc 30. This will transmit power from the motor to the shaft 6 through the gear wheel 19 and draw on the cable 12 in a direction to move the scoop or shovel 9 outward and into the material to be excavated, as indicated by dotted lines in Fig. 1. After the shovel has been given this straightforward thrust into the material and has thus picked up a load, the operator moves the lever 32 back to neutral 95 position to cut off the power to the shovel. 100

The next operation is for the operator to move the lever 44 from its neutral position outward away from the truck 1 and thereby 110 shift the friction disc 43 into engagement with the main disc 30 and the associated gear pinion into mesh with the gear wheel 42. When this has been done, the motor will turn the segmental racks 16 to raise the arms 8 and carry the shovel or scoop, while at the outer ends of the arms, into position above the machine and directed 115 backward to discharge or dump the load out of the shovel into a hopper or on a conveyor belt provided for carrying away the material as fast as it is excavated. When the shovel has reached this position, the operator moves the lever 44 back into neutral position to disconnect said gear train from the motor. 120

To return the shovel to its starting position, the operator, after the shovel has dumped itself, moves the lever 44 from neutral position inward toward the truck 1 to 125 shift the other friction disc 43^a into engage- 130

ment with the main disc 30 and thus connect the motor with the gear train including the segmental racks 16 and turns them in a direction to lower the arms 8 and carry the shovel downward into horizontal position in front of the machine, the shovel at this time being out at the forward ends of the arms. When this position has been reached, the lever 44 is returned to neutral position.

10 After the shovel 9 has been lowered into such position, the operator moves the lever 32 from neutral position inward toward the truck 1 to shift the friction disc 29^a into engagement with the main disc 30 and cause 15 the cable 12 to pull the shovel 9 back into starting position, as shown in Fig. 1.

Should it be desired to excavate from working places or corners on either side of the machine, the deck 4 is turned about the 20 pivotal connection between the links, as heretofore described, to move the shovel over toward whichever side of the machine the work is to be done. To move to the right-hand side of the machine, the lever 25 79 is moved from its neutral position in toward the truck 1 to bring the friction disc 77^a into engagement with the driving disc 78 and thus, through the gear train including the worm wheel 71, the pinion 70 travels along the stationary rack 64 in a 30 direction to swing the deck toward the right of the machine about the pivotal point 56, due to the arrangement of the bolster 52 and links 57 and 59, as heretofore described. 35 In Fig. 11, we have shown by dotted lines the deck 4 of the machine swung to a position with the shovel operating on the right-hand side of the machine, and in dotted lines, the bolster 52 in the position occupied 40 at that time. After the shovel has reached the position required at the right-hand side of the machine, the lever 79 is moved back into neutral position to cut out the motor from the gear train, and thus hold the shovel 45 in the position into which it has been swung. While the shovel is in that position, it is given a straightforward thrust, raised to dump, and brought back into the starting 50 position again, and those operations repeated as long as necessary by operating the levers 32 and 44, as heretofore described.

To bring the shovel back into a position directly in front of the machine from any 55 one of its adjusted positions at the right-hand side of the machine, the lever 79 is moved from neutral position outward from the truck 1 to move the friction disc 77 into engagement with the driving disc 78, and by the gear train described the pinion 70 60 will travel along the rack 64 back to the position shown in Figs. 1 and 10, whereupon the lever 79 is moved into neutral position to disconnect the motor from that gear train.

Should it be desired to excavate on the 65 left-hand side of the machine, the lever 79

is moved from neutral position out from the truck 1 as just described, and by the gear train mentioned, the pinion 70 will travel along the other side of the rack 64, and the deck, by reason of its connection with the 70 bolster 52, will then swing or pivot about the other pivotal point 58. After the deck has been swung to the point desired or permitted by the structure, the lever 79 is thrown back into neutral position to disconnect the motor from that gear train. 75

The machine described and shown, by reason of the arrangement and construction of the several parts, is made relatively low so that it can be used effectively in low working 80 places, such as in tunnels, mines, subways, or the like. The machine is simple in its construction and operation and therefore may be handled without great expense because unskilled labor can be used to operate it. 85 Then again, all of the operating parts are fairly well exposed to view and accessible, thereby permitting ready lubrication and repair to be made when needed. The fact that the various operations of the machine 90 are independent of each other and under the control of the operator, the shovel or scoop may be moved back and forth into and out of the material to be excavated several times, in order to pick up a full load, 95 before being raised into dumping position.

Another advantage of this construction resides in the fact that the fulcrum point of the lifting mechanism is positioned between the wheels 2, 2 on which the machine 100 is mounted, and therefore avoids the use of an extra weight to counterbalance the machine as the shovel is being raised with a load. This thereby reduces the amount 105 of material required to be placed in the machine when being built, and furthermore reduces the expense of building, as well as reduces the weight of the machine to a minimum so that a great deal of power is not required to move it over the rails. Furthermore, a relatively light clamp may be used 110 to hold down the rear end of the machine. Another advantage resides in the fact that the gear ratio may be made such as to reduce to the minimum the amount of power 115 required to move the several parts of the mechanism.

Another advantage arising out of the construction is that the shovel may be swung to either side of the truck 1 and thereby be used to excavate from working places on opposite sides of the machine. This is especially advantageous when cutting around curves, as when excavating from a drift into an enlarged compartment or chamber. The deck being swung on pivotal points adjacent the sides of the truck, instead of at the center, allows the scoop to reach places farther from the sides of the truck than could be done with only one pivotal point and 120

that in the center line of the truck.

Other and further advantages will be apparent to those skilled in the art to which our invention relates, and, while we have 5 shown and described in detail herein an excavating machine embodying the features of our invention, yet it is to be of course understood that the various details of construction and arrangement of parts may be variously changed and modified without departing from the spirit and scope of our invention.

We claim as our invention:

1. An excavating machine, comprising a truck, a deck above the same, power actuated excavating means carried by the deck, and means pivotally connecting the deck with the truck at two points, one adjacent each side of the truck so that the deck may be 20 swung horizontally to carry the excavating means to either side of the truck on the pivotal point nearest the side of the truck beyond which the excavating means is swung.

2. An excavating machine, comprising a truck, a deck above the same, power actuated excavating means carried by the deck, a member fixed to the truck and having a curved track, a bolster connected with the 30 deck and engaging said track, and means pivotally connecting said bolster with said member at two points, one adjacent each end of said bolster, so that the deck may be swung horizontally to carry the excavating means to either side of the truck on the pivotal point nearest the side of the truck beyond which the excavating means is swung.

3. An excavating machine, comprising a truck, a deck above the same, power actuated 40 excavating means carried by the deck, a member fixed to the truck and having a curved track, a bolster connected with the deck and having rollers engaging said track, means pivotally connecting said bolster with said member at two points, one adjacent each end of the bolster so that the deck may be swung horizontally on either pivotal point, and power actuated means for swinging said deck on said pivotal points.

4. An excavating machine, comprising a truck, a deck above the same, power actuated excavating means carried by the deck, a member fixed to the truck and having a curved track, a bolster connected with the 55 deck and having rollers engaging said track, means pivotally connecting said bolster with said member at two points, one adjacent each end of the bolster so that the deck may be swung horizontally on either pivotal point, a curved rack fixed on the truck, and a gear wheel carried by the deck and in mesh with said rack.

5. An excavating machine, comprising a truck, a deck above the same, power actuated 60 excavating means carried by the deck, a

member fixed to said truck and having a cross-bar at its inner end and a curved track in the forward part of the same, said cross-bar having forwardly projecting lugs, at different levels and adjacent the ends of the 70 same, a bolster above said lugs and connected with the deck and having rollers engaging said track, and links pivotally connected with said bolster and said lugs so that the deck may be swung horizontally on either of 75 two pivotal points, one adjacent each end of said bolster.

6. An excavating machine, comprising a truck, a deck above the same, power actuated excavating means carried by the deck, a member 80 fixed to said truck and having a cross-bar at its inner end and a curved track in the forward part of the same, said cross-bar having forwardly projecting lugs, at different levels and adjacent the ends of the 85 same, a bolster above said lugs and connected with the deck and having rollers engaging said track, and two links, one pivoted at one end to one lug and pivoted at the other end to the end of the bolster opposite said lug, 90 the other link being pivoted at one end to the other lug and pivoted at the opposite end to the end of the bolster opposite the last mentioned lug.

7. An excavating machine, comprising a 95 truck, a deck above the same, power actuated excavating means carried by the deck, a member fixed to said truck and having a cross-bar at its inner end and a curved track in the forward part of the same, said cross-bar having forwardly projecting lugs, at different levels and adjacent the ends of the 100 same, a bolster above said lugs and connected with the deck and having rollers engaging said track, links pivotally connected with 105 said bolster and said lugs so that the deck may be swung horizontally on either of two pivotal points, one adjacent each end of said bolster, a curved rack fixed on the truck in the rear of said cross-bar, and a gear wheel 110 carried by said deck and in mesh with said rack.

8. An excavating machine, comprising a truck, a deck above the same, an arm pivoted at its inner end and carried by said 115 deck, a scoop connected with said arm and adapted to be moved by the same into and out of dumping position above said deck, power actuated means for raising and lowering said arm, and means pivotally connecting said deck with said truck at two points, one adjacent each side of the truck, so that the deck may be swung horizontally to carry the scoop to either side of the truck on the pivotal point nearest the side of the 120 truck beyond which the scoop is swung.

9. An excavating machine, comprising a truck, a deck above the same, an arm pivoted at its inner end and carried by said 125 deck, a scoop connected with said arm and

- adapted to be moved by the same into and out of dumping position above said deck, power actuated means for raising and lowering said arm, a member fixed to said truck 5 and having a curved track, a bolster connected with said deck and having rollers engaging said track, means pivotally connecting said bolster with said member at two points, one adjacent each end of said bolster 10 so that the deck may be swung horizontally on either pivotal point, a curved rack fixed to said truck in the rear of said track, and a gear wheel carried by said deck and in mesh with said rack.
- 15 10. An excavating machine comprising a deck, a pair of laterally spaced arms pivoted at their inner ends and carried by said deck, a scoop located between said arms and connected therewith in a manner permitting 20 said scoop to be moved endwise thereof, power actuated means for moving said scoop endwise of said arms and for raising and lowering said arms for moving said scoop into and out of dumping position above said 25 deck, and manually operable means for controlling the application of power to said scoop and said arms.
11. An excavating machine, comprising a deck, upright standards secured to said 30 deck, a shaft extending between and journaled in said standards, a pair of laterally spaced arms having their inner ends journaled on said shaft, a scoop located between said arms and connected therewith in a 35 manner permitting said scoop to be moved endwise thereof, sheaves fixed on said shaft, one adjacent each arm, guide rollers on each arm, a cable for each arm and having its ends connected with said scoop and trained 40 over said rollers and sheave of the associated arm, power actuated means for rotating said shaft and for raising and lowering said arms for moving the scoop into and out of dumping position above the deck, and 45 manually operable means for controlling the application of power to said scoop and arms.
12. An excavating machine, comprising a deck, standards secured to said deck, two 50 shafts extending between and supported by said standards, a pair of laterally spaced arms having their inner ends journaled on one of said shafts, a scoop between said arms and connected therewith in a manner to be moved endwise thereof, segmental racks on the other of said shafts, one for each of said arms, each rack being connected with its associated arm intermediate the ends thereof, power actuated means for moving said 55 scoop endwise of said arms and for turning said racks, and manually operable means for controlling the application of power to said scoop and said racks.
13. An excavating machine, comprising a 60 deck, standards secured to said deck, two shafts extending between and supported by said standards, a pair of laterally spaced arms having their inner ends journaled on one of said shafts, a scoop between said arms and connected therewith in a manner to be moved endwise thereof, segmental racks on the other of said shafts, one for each of said arms, each rack being connected with its associated arm intermediate the ends thereof, power actuated means for moving said scoop endwise of said arms and for turning said racks, and manually operable means for controlling the application of power to said scoop and said racks.
14. An excavating machine, comprising a deck, standards secured to said deck, two shafts extending between and supported by 65 said standards, a pair of laterally spaced arms having their inner ends journaled on one of said shafts, a scoop between said arms and connected therewith in a manner to be moved endwise thereof, segmental racks on the other of said shafts, one for each of said arms, each rack being connected with its associated arm intermediate the ends thereof, power transmitting mechanism, one between said motor and the shaft on which the arms are mounted, and the other between the motor and said racks, said mechanisms including means whereby the motor may drive either one of said mechanisms 70 in either direction and independently of the other.
15. An excavating machine, comprising a deck, standards secured to said deck, two shafts extending between and supported by 75 said standards, a pair of laterally spaced arms having their inner ends journaled on one of said shafts, a scoop between said arms and connected therewith in a manner to be moved endwise thereof, segmental racks on the other of said shafts, one for each of said arms, each rack being connected with its associated arm intermediate the ends thereof, a gear wheel on the shaft on which said arms are mounted, a cable for each arm and having its ends connected with said scoop and actuated upon the turning of said gear wheel, a counter-shaft to the rear of said racks, pinions on said counter-shaft and in mesh with said racks, 80 a gear wheel on said counter-shaft, a motor, two gear trains, one for each of said gear wheels and between the same and said motor, and means for shifting either of said gear trains in operative connection with 85 said motor.
16. An excavating machine, comprising a truck, a deck above the same, a pair of laterally spaced arms having pivotal connection at their inner ends with said deck, a scoop between said arms and connected therewith in a manner permitting the scoop to be moved endwise thereof, means for moving said scoop endwise of said arms, means for raising and lowering said arms for moving the scoop into and out of dumping position above the deck, means for pivotally connecting the deck with said truck so that the deck may be swung horizontally to carry the scoop to opposite sides of the truck, a motor on said deck for operating all of said means, and means manually controlled whereby the motor may operate any of said means independently of the others. 90
17. The combination with a motor having a shaft with a friction disc thereon, of a gear shifting device, comprising a slidably mounted open frame having an elongated slot in one side thereof, a driven shaft extending into said frame through said slot 95

and having a gear wheel fixed thereto within said frame, gear pinions on the shaft journaled in said frame on opposite sides of said gear wheel and adapted to be moved with said frame into and out of mesh therewith, friction discs fixed on the shaft carried by said frame and arranged on opposite sides of the friction disc on said motor shaft and moved into and out of contact with said last mentioned disc in the movement of said frame, and a manually operable lever connected with said frame for moving the same.

In testimony that we claim the foregoing as our invention, we affix our signatures this 10th day of March, A. D. 1921.

JAMES A. MACKILLICAN.
